UNITED STATES PATENT OFFICE

ROBERT M. KINNARD AND FRANK M. KINNARD, OF SEBRING, OHIO

CLAY SPREADER

Application filed October 3, 1929. Serial No. 397,039.

The invention relates to spreaders for use in potteries for batting out clay, preparatory to placing the clay in the molds for forming dishes and the like, and more particularly to

5 improvements over Letters Patent No. 1,430,309 issued September 26, 1922, to Frank M. Kinnard, Letters Patent No. 1,481,913 issued January 29, 1924, to Frank M. Kinnard and Robert M. Kinnard and Letters

10 Patent No. 1,513,602 issued October 28, 1924, to Frank M. Kinnard and Robert M. Kinnard.

The patents above referred to show clay spreaders provided with a spreader tool and 15 a stationary block for receiving a ball of clay, either the tool or the block being movable toward the other for spreading the clay ball to form a bat therefrom, the block in each case having only a single working face.

20 The object of the present improvement is to provide a clay spreader comprising a spreader tool mounted upon a shaft journaled in a stationary framework, a double-faced block being mounted for swinging and rotary movement whereby a ball of clay may be placed upon one side of the block, the block being then rotated to bring the ball of clay into engagement with the spreader tool while the finished bat is removed from the other side of 25 the block and a new ball of clay placed thereon, thus considerably speeding up the operation of the apparatus.

The above and other objects may be attained by constructing the apparatus in the 30 manner illustrated in the accompanying drawings, in which

Figure 1 is a perspective view of the improved clay spreader;

Fig. 2, a vertical sectional view through the 35 same;

Fig. 3, a fragmentary section on the line 3—3, Fig. 2;

Fig. 4, a vertical section through the upper 40 portion of the machine taken substantially at right angles to Fig. 2;

Fig. 5, a top plan view of the apparatus;

Fig. 6, a detached plan view of the spreader tool; and

Fig. 7, a detail perspective view of one of

the cam plates for controlling the rotation of the double-faced block.

Similar numerals refer to similar parts throughout the drawings.

The machine is mounted upon a base 10, 55 preferably in the form of a hollow casting, having the bearing bracket 11 located at one side, preferably near the lower end thereof, and provided with the spaced bearings 12.

The drive shaft 13 is journaled in the bearings 12 and a thrust plate 14 and set screw 15 may be provided for contact with the outer end of the shaft for taking up the end thrust.

A friction disk 16 is fixed upon the inner end of the drive shaft, within the hollow base, 65 and frictionally contacts with the friction pulley 17 mounted upon the vertical shaft 18, the lower end of which may be journaled in a bearing 19 at the bottom of the base.

The upper end of the shaft 18 is keyed or 70 splined to the tubular shaft 20 which is vertically slidable upon the shaft 18.

The tubular shaft 20 is journaled at its lower portion within the bearing 21 carried by the vertically movable bracket 22, a collar 75 23 being fixed upon the tubular shaft above and below the bearing 21.

The bracket 22 is provided with a nut 24 engaged by the vertical adjusting screw 25 journaled in bearings 26 within the base and provided with a hand wheel 27 for rotating the screw in order to raise or lower the bracket 22 and with it the tubular shaft 20.

The upper end portion of the tubular shaft is journaled in a bearing 28 which may be 85 fixed upon the top of the hollow base and the spreader tool indicated generally at 29 is carried by the upper end of said shaft.

This spreader tool comprises the hub portion 30 and the radially disposed wings 31 which may be formed integral with the hub. The hub and wings may be formed of cast aluminum or the like, each wing being provided with the beveled upper face 32 upon which is fixed a hardened blade 33.

A curved guard plate 34 may surround the spreader tool above the top of the base, and a pair of spaced bracket arms 35 extend rearwardly from said guard plate and may be 100

provided with a table or shelf 36 at their upper ends for receiving tools or the like.

The frame 37 is pivoted between the bracket arms as by the shaft 38 and provided with the spaced bearings 39 within which is journaled the shaft 40 carrying the circular clamp 41 at its free end. The double-surfaced block 42 is clamped within the clamp ring 41 and provided with the two working surfaces 43 and 44 located at opposite sides of the block. A handle 45 is fixed upon the clamp ring for operating the block.

A pair of similar cam plates 46 are carried by the bracket arms 35 for cooperation with the stud 47 extending through opposite sides of the shaft 40.

A pair of oppositely disposed caps 48 and 49 may be mounted upon the outer end of the shaft 40, a coil spring 50 being interposed between the caps and a screw 51 being provided for holding the cap 49 upon the shaft and adjusting the tension of the spring.

For the purpose of moistening the clay ball, a water pipe 52 may be provided, terminating in the reduced nozzle portion 53 adapted to spray a fine stream of water upon the tool. In order to intermittently operate this stream of water, the valve 54 may be provided with a stem 55 connected to the shaft 38.

Thus as the frame 37 is swung upon its pivot, the valve 54 may be intermittently opened and closed to spray water upon the spreader tool as the block is lowered into operative position.

In operating the machine, the shaft 13 may be continuously driven from any suitable source of power connected by a belt or the like to the drive pulley 56 continuously rotating the spreader tool. With the block in lowered position as shown in Figs. 2, 4 and 5, a ball of clay of suitable size is placed upon the top surface 43 of the block. The handle 45 is then grasped and the block is raised to the broken line position shown in Fig. 4.

At this point the pin 47 is disengaged from the cam plates 46 and the block is rotated upon the axis of the shaft 40, bringing the surface 43 on the under side of the block and the surface 44 on the top thereof. The frame 37 is then swung back into the normal position, the pin 47 engaging the cam plates 46 and preventing further rotation of the shaft as the block reaches the operative position.

The ball of clay carried by the surface 43, which is now upon the under side of the block, is engaged by the rotating spreader tool and quickly spread and formed into a thin bat of uniform thickness having a smooth surface, the clay having been moistened by the spray of water from the nozzle 42 upon the tool as the block is lowered into position.

While the bat is being formed upon the

under side of the block the finished bat is removed from the upper side and a new ball of clay placed thereon and the operation is continued as above described.

In this way it will be seen that the operation of the machine is greatly speeded up as the finished bat is removed and a new ball of clay placed upon the block while a bat is being formed upon the under side of block. Thus the machine is never idle to permit removal of the finished product and the placing of new material in position.

The counterweight 57 upon the frame 37 counterbalances the weight of the block 42 and assists the operator in raising and lowering the block.

We claim:

1. A spreader including a rotating spreader tool and a movable block having opposite working faces arranged to be alternately moved into position adjacent to the spreader tool.

2. A spreader including a rotating spreader tool mounted upon a vertical axis and a movable block having opposite working faces arranged to be alternately moved into horizontal position adjacent to the spreader tool.

3. A spreader including a rotating spreader tool, a movable block arranged to be moved into position adjacent to the spreader tool and means for spraying water upon the tool.

4. A spreader including a rotating spreader tool, a movable block having opposite working faces arranged to be alternately moved into position adjacent to the spreader tool, and means controlled by the movement of the block toward the spreader tool for spraying water upon the tool.

5. A spreader including a rotating spreader tool and a pivoted block having opposite working faces arranged to be alternately moved into position adjacent to the spreader tool.

6. A spreader including a rotating spreader tool, a pivoted frame, and a block swivelled upon the frame and having opposite working faces arranged to be alternately moved into position adjacent to the spreader tool.

7. A spreader including a rotating spreader tool, a pivoted frame, and a block mounted upon the frame and having opposite working faces arranged to be alternately moved into position adjacent to the spreader tool.

In testimony that we claim the above, we have hereunto subscribed our names.

ROBERT M. KINNARD.
FRANK M. KINNARD.
